UNITED STATES PATENT OFFICE.

HARVEY B. REPPETTO, OF WHEELING, WEST VIRGINIA, ASSIGNOR TO WHITAKER-LESSNER COMPANY, OF WHEELING, WEST VIRGINIA, A CORPORATION OF WEST VIRGINIA.

BURNER FOR OIL STOVES.

1,402,316.

Specification of Letters Patent. Patented Jan. 3, 1922.

Application filed April 19, 1921. Serial No. 462,527.

To all whom it may concern:

Be it known that I, HARVEY B. REPPETTO, a citizen of the United States of America, and resident of Wheeling, county of Ohio, 5 and State of West Virginia, have invented certain new and useful Improvements in Burners for Oil Stoves, of which the following is a specification.

This invention relates broadly to oil 10 stoves, and more particularly to a burner mechanism for such stoves.

The invention is directed to vertically movable oil burners of the type which embodies a head of circular trough form 15 mounted upon a telescopic feed tube and carrying in the trough thereof an incombustible wick, and it has for its primary object to provide improved means for adjusting the elevation of the burner head and whereby 20 the latter is maintained in its adjusted position.

A further object is to provide a structure of the character mentioned which involves a minimum number of parts and which is 25 relatively simple in construction and inexpensive to manufacture.

With these and other objects in view, the invention resides in the features of construction, arrangement of parts and combinations 30 of elements which will hereinafter be fully described, reference being had to the accompanying drawings in which—

Figure 1 is a transverse section of an oil stove embodying my invention;

Figure 2 is a front elevation of the same, partly in broken section;

Figures 3 and 4 are enlarged sections taken, respectively, on lines 3—3 and 4—4, Fig. 2;

Figure 5 is an enlarged outer face view of the lever-engaging bracket, detached;

Figure 6 is an enlarged section taken substantially on line 6—6, Fig. 1, showing the invention partly in top plan and partly in 45 broken section;

Figure 7 is a section taken substantially on line 7—7, Fig. 6; and—

Figure 8 is a section on line 8—8, Fig. 7.

Referring to said drawings, 1 indicates 50 the front wall, and 2 the bottom of the stove casing, which is ordinarily constructed of sheet metal and is supported by legs 3. Disposed horizontally on the bottom 2 is a sup-

ply pipe 4 leading from an oil reservoir 5 which is supported at a suitable elevation 55 outside the stove casing. Rising from said supply pipe is one or more branches or stand-pipes 6, each of which has telescopically mounted therein a vertical tube 7 which constitutes a support for a burner head or 60 trough 8 and which opens into said trough for supplying oil in the usual well-known manner, said stand-pipe having the usual or any suitable form of packing gland, as 9, at its upper end.

Attached to the burner head 8, as by brazing or by means of bolts or rivets 10, is the upper end of a bracket 11 which embodies two depending wings of right-angle form in horizontal section, one such wing being 70 located on each of two opposite sides of the tube 7. Each of the radially extending blades or members 12 of said wings is provided with a vertically extending slot 13 through which extends one of the resilient 75 fingers 14 of a forked operating lever 15 which is pivotally mounted intermediate its ends and which has its outer end projected outward through a vertical slot 16 provided therefor in the front wall 1 of the stove 80 casing.

Said slots 13 in the wing-members 12 are located adjacent to the angle formed by said members with the forwardly extending terminal members 17, so that the opposite forks 85 or spring fingers 14, which normally tend to separate, or to incline outward away from each other, lie in frictional binding relation to said members 17 for resisting the relative movement which results when the burner 90 head 8 is raised or lowered.

While any preferred mounting may be provided for the lever 15, I have herein shown a support which constitutes the subject-matter of an application, Serial No. 95 562,564, filed Apr. 19, 1921, by W. W. Hollo-way and Henry Kielberg, the same comprising a one-piece sheet-metal bracket 18 having tongues 19 struck up from the body thereof and bent to form supporting mem- 100 bers upon which the lever is pivoted.

Said lever 15 is composed of a strip of sheet-metal and has its body, or that portion intermediate the oppositely disposed spring fingers 14 and the finger-piece 20 provided 105 at the outer end, formed by doubling the

strip longitudinally upon itself along its median line, as shown.

Bolted to the inner face of the front casting wall 1 is a bracket 21 having a vertically disposed inwardly extending wing 21^a having a face thereof flush with one edge of the slot 16 provided in said wall. Formed in said wing is a series of pressed-in sockets 22 adapted for the reception of a bead or button 23 formed on the adjacent side of the lever 15. Said sockets 22 are disposed in an arcuately curved line corresponding to the arc through which said button 23 moves with elevating and lowering movement of the lever. As said lever is elevated or lowered from one limit to the other, said button successively seats in said sockets, and, when so seated, considerable force is required to unseat it for effecting further movement. Thus, said lever and said bracket 21 provide means auxiliary to the spring finger device hereinbefore described for effectively holding the burner head in position against chance elevating and lowering movement.

25 What is claimed is—

1. In a burner of the character described, a vertically movable burner head, members carried in fixed relation to said burner head, a pivoted operating lever, and oppositely disposed resilient fingers carried by said lever, said fingers being disposed to coact with said members for shifting the position of the burner head when said lever is actuated and having said fingers in frictional bearing relation thereto for holding said head in adjusted position.

2. In a burner of the character described, a vertically movable burner head, angular wings carried in fixed relation to said burner head, a pivoted operating lever, and oppositely disposed resilient fingers interengaged with one member of each wing and disposed in frictional bearing engagement with the other member, said fingers being adapted, upon actuation of said lever, to raise or lower said burner head against the frictional resistance offered by said finger-engaging members.

3. In a burner of the character described, a vertically movable burner head, a pivoted operating lever having oppositely disposed resilient fingers, and means carried in fixed relation to said burner head and interengaged with said fingers whereby the elevation of the former is adjusted through operation of said lever, said means including portions whereon said fingers exert yielding pressure for frictionally resisting movement of said parts from adjusted position.

60 4. In a burner of the character described, a vertically movable burner head, a pivoted operating lever having its inner end forked forming oppositely disposed resilient fingers, and a bracket disposed in fixed relation to said burner head and embodying a pair of

wings, said wings being apertured to receive said fingers and having portions in permanent frictional engagement with said fingers.

5. In a burner of the character described, a stand pipe, a feed pipe vertically movable in said stand pipe, a burner head carried by said feed pipe, wings depending from said burner head, a support, an operating lever pivoted intermediate its ends on said support, said lever having oppositely disposed spring fingers on its inner end, said fingers being engaged with said wings for imparting movement to said burner head through actuation of said lever, and means for maintaining said parts in adjusted position. 80

6. In a burner of the character described, a stand pipe, a feed pipe vertically movable in said stand pipe, a burner head carried by said feed pipe, wings depending from said burner head, said wings being of right angle 85 form in horizontal section and one member of each wing having an aperture therein, a support, a lever pivoted intermediate its ends on said support, and spring fingers carried by said lever projected through the 90 apertures of said wing members, said fingers also being disposed in yielding pressure-exerting relation to the other members of said wings whereby relative movement of said parts is frictionally resisted. 95

7. In a burner of the character described, a stand pipe, a feed pipe vertically movable in said stand pipe, a burner head carried by said feed pipe, wings depending from said burner head, a support, an operating lever 100 pivoted intermediate its ends on said support, said lever having oppositely disposed spring fingers on its inner end, said fingers being engaged with said wings for imparting movement to said burner head through 105 actuation of said lever, portions of said wings being disposed to frictionally retard movement of said fingers for preventing chance displacement of the burner head from adjusted position. 110

8. The combination with a vertically movable burner head having depending wings, of a pivoted lever operatively associated with said wings for effecting elevating and lowering movements of said burner head, 115 said lever being formed of a single piece of sheet metal having its inner end divided longitudinally to form end members, the body portion of said lever being doubled longitudinally upon itself and the end members 120 being bent to form oppositely disposed resilient fingers which are disposed to exert yielding pressure on portions of said wings for frictionally resisting relative movement of said parts from adjusted positions. 125

9. In a burner of the character described, a stand pipe, a feed pipe vertically movable in said stand pipe, a burner head carried by said feed pipe, wings depending from said burner head, a support, an operating lever 130

pivoted intermediate its ends on said support, said lever having oppositely disposed spring fingers on its inner end, said fingers being engaged with said wings for imparting movement to said burner head through actuation of said lever, portions of said wings being disposed to frictionally retard movement of said fingers for preventing chance displacement of the burner head from

adjusted position, and auxiliary means engaged with said lever for retarding shifting movement of the latter. 10

In testimony whereof, I affix my signature in presence of two subscribing witnesses.
